UNITED STATES PATENT OFFICE.

BERNARD D. KNOWLES, OF NEW YORK, N. Y., ASSIGNOR TO C. B. COTTRELL & SONS COMPANY, OF NEW YORK, N. Y., A CORPORATION OF DELAWARE.

ANTISMUTTING DEVICE FOR TRAVELING SHEETS.

1,342,117.

Specification of Letters Patent.

Patented June 1, 1920.

Application filed November 6, 1915. Serial No. 60,074.

To all whom it may concern:

Be it known that I, BERNARD D. KNOWLES, a citizen of the United States, and resident of the borough of Manhattan, in the city and 5 State of New York, have invented a new and useful Improvement in Antismutting Devices for Traveling Sheets, of which the following is a specification.

The object of my invention is to provide 10 a novel means for preventing the smutting of traveling sheets, and it is particularly intended for use in preventing the smutting of sheets as they are passed first in one direction and then in another direction 15 through the folding mechanism of a folding machine, which means is arranged to present a rolling support for a sheet traveling first in one direction and next in another direction at an angle thereto. 20 My invention more particularly consists 25 in a device comprising a rotary wheel having an annular series of rotary disks, the axes of which disks are at right angles to the axis of the rotary wheel, so that when the device is engaged with a sheet traveling 30 in one direction, the wheel will rotate and when the sheet is traveling in another direction at right angles to its first direction, the particular disk or disks which engage 35 the sheet will rotate, while the wheel may remain stationary.

A practical embodiment of my invention is illustrated in the accompanying drawings in which the embodiment is shown as 40 applied to a folding machine of well known construction.

Figure 1 is a detail vertical section taken from front to rear through so much of a sheet folding machine as will illustrate the 45 application of my invention.

Fig. 2 is a detail horizontal section taken in the plane of the line A—A of Fig. 1.

Fig. 3 is a detail transverse section taken in the plane of the line B—B of Fig. 1.

Fig. 4 is a plan view of one of my anti-smutting devices.

Fig. 5 is a side view of the same, and

Fig. 6 is a section taken in the plane of the line C—C of Fig. 5.

50 In the folding machine in connection with which I have chosen to illustrate my invention, the sheets are fed longitudinally on to the folding table 1, into engagement with the front stop 2, by the usual upper and

lower marginal endless tape carriers 3 and 4, into position over the folding slot 5 in the table, between the longitudinally arranged stationary folding blades 6 and the reciprocating folding grippers 7, which grippers are operated by any well known or approved means. These folding grippers 7 60 coact with the stationary folding blades 6, through the slot 5, in the table 1, to first crease the sheets longitudinally of their travel over the edge of the folding blade 65 along the intended line of fold, and to afterward complete the folding of the so creased sheet by drawing it from the folding blade through said slot in the table and to thereafter deliver the so folded sheet to any desired point. 70

As the freshly printed sheet is moved longitudinally along the table into engagement with the front stop, and then laterally by the folding of the sheet through the table, 75 the printed matter on the under side of the sheet is liable to come into contact with the table and become smutted. I have provided a rolling support for the sheet, both as it is moved longitudinally into its folding position and also when it is moved laterally during its folding operation, which support I will now describe in connection with the folding machine herein illustrated and described. 85

A bracket 8 is provided with a stud axle 9, on which axle is mounted the hub 10 of a rotary wheel 11. This rotary wheel 11, 90 may be held in position on the stud 9, by a washer 12 and screw 13. This wheel is provided with an annular series of radial slots 14 opening through its periphery and the periphery of the wheel is provided with a shallow groove 15 in which is seated a split ring 16. This split ring may be fixed against 95 rotative movement on the wheel 11, as for instance, by providing the wheel with a stud or pin 17 interposed between the ends of the split ring 16. This ring 16 is preferably made of spring material so as to snugly 100 seat in the peripheral groove 15 of the wheel.

An annular series of radial disks 18 are rotatively mounted on the split ring 16, which disks are preferably toothed so as to 105 present a very small engaging surface to the sheet traveling over the same. The inner portions of these disks are located within

the radial slots 14 of the wheel, and the outer portions of these disks project beyond the split peripheral ring 16 of the wheel.

In the accompanying drawings I have shown two of these antismutting devices attached to each of two bars 19, arranged longitudinally of the folding table 1, across the folding slot 5 upon opposite sides of the folding blade and its coöperating grippers, the parts being so arranged that the disks 18 on the wheel 11 project above the surface of the table into position to engage the under side of the sheet as it travels into its folding position on the table. It will be understood that any number of these devices may be employed and that they may be located in any desired position on the table.

It will be seen that these antismutting devices not only serve to prevent the smutting of the under side of the sheet by contact with the table, but also serve as an anti-

friction support for the sheet as it is traveling in both of its directions on the said table.

What I claim is:

1. An antismutting device for traveling printed sheets including a rotary wheel having a peripheral split ring, a plurality of radial disks rotatably mounted on said ring and means for maintaining the split ring in position on the wheel. 25

2. An antismutting device for traveling printed sheets including a rotary wheel having a peripheral split ring, a plurality of radial disks rotatably mounted on said ring, 35 and a pin or stud on said wheel interposed between the ends of the split ring for maintaining the ring in position on the wheel.

In testimony, that I claim the foregoing as my invention, I have signed my name, 40 this 5th day of November, 1915.

BERNARD D. KNOWLES.
